FLEXIBLE CHAIRS

George A. Dusenbury, Saluda, N. C.

Application May 13, 1953, Serial No. 354,844

3 Claims. (Cl. 155—187)

This invention relates to flexible chairs of the type comprising canvas or similar flexible material slung between frame members of metal, wood, or the like.

It has long been a problem in the flexible furniture field to devise a simple and easily manufactured chair which would provide a high degree of comfort to the sitter. In such flexible furniture comfort is obtainable only when the body is evenly supported so that there are no loads to tense the body muscles and no points of furniture pressure to cause body discomfort. Heretofore even support of the body has been accomplished through the use of cushions comprising compressible springs, pads, or a combination of springs and pads, supported on a rigid chair frame. Such chair manufacture has been a laborious procedure, and the finished product has been characterized by excessive weight.

To reduce manufacturing costs and the weight of the finished product, chairs have been devised using flexible material, such as canvas, for the body engaging portions, this flexible material being slung between rigid, or semi-rigid, frame members. However, such chairs have not been successful from a comfort standpoint, for even body support has been largely overlooked. In some of these chairs the design has permitted flexibility of the frame to absorb a portion of the sitter's weight, but soft, buoyant cushioning throughout seat and back has largely depended upon the resilience of body engaging cushions in compression.

Accordingly, it is the primary object of my invention to provide a flexible chair of light weight which gives uniform body support and which may be manufactured economically with a minimum of labor. This object is accomplished by employing a chair design embodying a flexible material for the body engaging portions and a resilient frame upon which this material is slung. In my novel chair the frame is the sole source of cushioning, and uniform body support is assured.

Thus, it is an object of my invention to provide a chair having flexible seat and back portions fixed on a resilient frame which will permit relaxation or tightening of the seat and back according to the distributed weight of the sitter. I accomplish this object by fabricating a chair frame comprising a first upstanding resilient U-shaped member to form the front legs and a second similar U-shaped member to form the rear legs. Between the upper portions of corresponding front and rear leg members L-shaped side members are connected, and it is between these L-shaped side members that the flexible seat and back material is slung to form seat and back membranes. The side members are so connected that application of weight to the seat membrane only will cause it to sag downwardly, with a corresponding tightening of the back membrane. If the sitter then leans backwardly, the back membrane will tend to sag according to the weight distribution.

Other and further objects, features and advantages will be apparent from the description which follows, read in connection with the accompanying drawings in which

2

Figure 1 is a front elevation showing the preferred embodiment of my novel chair;

Figure 2 is a side elevation of the chair shown in Figure 1;

Figure 3 is an enlarged cross section, partly broken away, taken along the line 3—3 of Figure 2;

Figure 4 is an enlarged fragmentary cross section taken along the line 4—4 of Figure 2;

Figure 5 is a front elevation of my improved chair showing in dotted lines the movement of the chair upon the application of weight to the seat portion;

Figure 6 is a plan view showing in full and dotted lines the respective portions of the chair in Figure 5;

Figure 7 is a front elevation of my chair showing in full lines the position of the respective chair members upon the application of weight to the seat of the chair and showing in dotted lines the final position of the chair members when weight is applied to the back member; and

Figure 8 is a plan view showing in full and dotted lines the respective portions of the chair in Figure 7.

To facilitate an understanding of my invention, one embodiment thereof is described in the specification and shown in the accompanying drawings. It will nevertheless be understood that no limitation of the invention is thereby intended and that various changes and alterations are contemplated such as would ordinarily occur to one skilled in the art to which the invention relates.

Referring to the drawings, and more particularly to Figures 1 and 2, the preferred embodiment of my flexible chair structure is shown. A resilient chair frame structure is employed, this structure being designed to absorb the weight of a sitter in accordance with the distribution of weight on the seat and back members. The frame comprises two resilient U-spring members 1 and 2 and a transverse member 3 fixed to and connecting the U-spring members. Each U-spring comprises two upstanding legs, as portions 1a and 1b of spring 1, and a web portion between the upstanding portions as shown at 1c. Each upstanding member serves as one chair leg, the upstanding members of spring 1 serving as the front legs and the upstanding members of spring 2 serving as the rear legs.

In my preferred embodiment the terminal ends of the upstanding spring portions are bent outwardly, as at 1d and 1e, to serve as support members for the arm rests 4 and 5. Within each such outwardly bent portion an elongated aperture is formed, as at 6 in Figure 3. The arm rests are secured to corresponding front and rear outwardly extending spring portions for pivotal or relative movement to such spring portions by bolts 7 passing through the arm rest and through the elongated aperture in the outwardly extending spring portion. These connection details are best seen at 7 in Figures 3 and 4. This method of connecting the arm rest allows relative movement between the arm rests and the U-shaped springs so that the resilience of the springs is not impeded by the arm rest connections.

The support frame hereinbefore described serves as a mounting for the seat and back portions 8 and 9, respectively, of the chair.

The seat and back portions comprise flexible membranes of canvas or the like; supported on and extending between the substantially L-shaped members 10 and 11. The L-shaped members 10 and 11 may be fabricated from any suitable material, such as rod stock, and preferably each member is pivotally secured to one front leg and its corresponding rear leg. As seen in Figure 2, the front leg attachment is made on the seat portion of the L-rod at a point intermediate the seat ends. The rear leg attachment is made on the back portion of the L-rod at a point fairly close to the bottom of the back. Preferably these connections comprise eyebolts, as shown at 12 in Figure 4 or 14 in Figure 3, the eye portion of which en-

compasses the L-shaped rod 10 and the shank portion of which extends through an aperture on the upstanding front and rear spring portions. A nut threaded on the eye-bolt, as at 13 in Figure 4 or 15 in Figure 3, serves to complete the union, adjustment of the nut determining tension of the seat and back membranes and the U-spring members.

In conventional flexible chairs of the class described application of weight to the seat portion tends to cause the seat membrane to bulge downwardly and in turn effects a corresponding sagging of the back membrane. Because of the resilient frame structure hereinbefore described uniform support is provided by seat and back membranes 8 and 9 according to the load distribution on these membranes, and there is no corresponding sagging of the back membrane when weight is applied to the seat alone. Referring to Figures 5 and 6, my chair is shown in full lines when in a non-loaded state. Upon application of a load to the seat, membrane 8 will tend to bulge as shown in dotted lines 8a of Figure 5, and the upstanding portions 1a and 1b of front U-spring 1 will be drawn toward each other. Thus, L members 10 and 11 will be pivoted about their points of union to spring 2 at A and B effecting a tightening of back membrane 9 so that the chair assumes the position shown by dotted lines in Figures 5 and 6 and by full lines in Figures 7 and 8. If the sitter then leans back his weight will tend to bulge membrane 9 as in the dotted lines 9a of Figure 8. Such bulging of membrane 9 tends to draw the back portions of L-rods 10 and 11 toward each other and correspondingly draws the upstanding portions of U-spring 2 together. In this manner L-members 10 and 11 will be pivoted about their points of union to spring 1 at C and D. Thus, bulging or flexing of membranes 8 and 9 is effected according to the body contour of a sitter through the natural resiliency of the upstanding leg portions of the frame U-springs, resiliency of the U-springs permitting angular shifting of the L-members relative to one another.

Having thus described the invention, what is claimed as new and desired to be secured by Letter Patent is:

1. In a flexible chair a support frame, said frame comprising a first resilient U-shaped member having a ground engaging web and upstanding portions forming front legs, a second resilient U-shaped member having a ground engaging web and upstanding portions forming rear legs, and means connecting the webs of said first and second U-shaped members; two substantially L-shaped members each being separate from one another, means pivotally connecting each said member to an upper portion of a front leg and an upper portion of the corresponding rear leg; and flexible material slung between said L-shaped rods, said L-shaped members being coupled to each other

only through said support frame and said flexible material.

2. In a flexible chair a support frame, said frame comprising a first resilient U-shaped member having a ground engaging web and upstanding portions forming front legs, a second resilient U-shaped member having a ground engaging web and upstanding portions forming rear legs, the terminal ends of such front and rear upstanding portions being bent outwardly of the chair, two arm rests, each arm rest being pivotally connected to the terminal end of a front upstanding portion and the terminal end of its corresponding rear upstanding portion, and means connecting the webs of said first and second U-shaped members; two substantially L-shaped members each being separate from one another, means pivotally connecting each L-shaped member to an upper portion of a front leg and an upper portion of the corresponding rear leg; and flexible material slung between such L-shaped members, said L-shaped members being coupled to each other only through said support frame and said flexible material.

3. In a flexible chair a support frame, said frame comprising a first resilient U-shaped member having a ground engaging web and upstanding portions forming front legs, a second resilient U-shaped member having a ground engaging web and upstanding portions forming rear legs, the terminal ends of said front and rear upstanding portions being bent outwardly of the chair, two arms rests, each arm rest being connected to the terminal end of a front upstanding portion for relative movement thereto and the terminal end of its corresponding rear upstanding portion for relative movement thereto, and means connecting the webs of said first and second U-shaped members; two substantially L-shaped members each being separate from one another, means pivotally connecting each L-shaped member to an upper portion of a front leg and an upper portion of the corresponding rear leg; and flexible material slung between such L-shaped members, said L-shaped members being coupled to each other only through said support frame and said flexible material.
